CODED TRACK CIRCUIT RAILWAY
SIGNALING SYSTEMCrawford E. Staples, Homewood, Pa., assignor to
Westinghouse Air Brake Company, Wilmerding,
Pa., a corporation of Pennsylvania

Application February 11, 1953, Serial No. 336,225

3 Claims. (Cl. 246—33)

1

My invention relates to an automatic block signaling system of the coded type for single track railroads.

An object of my invention is to provide an improved system of the type described which can be installed and maintained at a minimum cost so that the system is available for use in track stretches where the number of trains operated is not sufficient to warrant installation of a more complete system.

Another object of my invention is to provide an improved system of the type described which is arranged so that the system is controlled entirely over the track rails in the single track stretches to thereby reduce the amount of line wire to be used.

A further object of my invention is to provide an improved system of the type described in which each of the track sections in a single track stretch is provided with two track circuits employing coded energy, one for each direction of traffic.

According to my invention I provide in a stretch of single track railway between two passing sidings, a station leaving and a station entering signal adjacent each passing siding and intermediate signals controlling train movements through the stretch. At each signal location, a pair of insulated joints is provided so that the stretch is divided into two end sections adjacent the passing sidings and an intermediate section between the two end sections. Each of the end track sections is provided with two track circuits, one for each direction of traffic, and each of these track circuits is provided with code transmitting means at opposite ends of the sections and track relay means at the end of the section opposite to the code transmitting means associated therewith. The track circuits from the passing sidings to the intermediate signals are of the polar coded type and the track relay means in these track circuits are selectively responsive to currents of opposite polarity. In this manner, the intermediate signals associated with their track circuits are provided with a third indication.

In the intermediate section, each end is provided with apparatus including code generating means, code halving means and code transmitting means. In addition, a code following track relay is provided at each end, responsive to the code being transmitted from the other end. Furthermore, at one end of the intermediate section, a reverse code generating means is also provided. Means is provided for connecting the code generating and halving means at the one end of the intermediate section to their asso-

2

ciated code transmitting means when a train occupies the end section adjacent the other end of the intermediate section or when a train occupies the intermediate section. Means is provided for connecting the code generating and halving means at the other end of the section to their associated code transmitting means except when the adjacent end section is occupied. Means is further provided for connecting the reverse code generating means to its associated code transmitting means when the entire stretch is vacant.

The track relay means at each end of each section controls the signal associated therewith.

Other objects of my invention will appear hereinafter as the characteristic features of construction and mode of operation of my invention are described in detail.

I shall describe one form of apparatus embodying my invention and shall then point out the novel features thereof in claims.

In the accompanying drawings, Figs. 1a and 1b when placed side by side in the named order, with Fig. 1a at the left, form a diagrammatic view showing one circuit arrangement embodying my invention.

Figs. 2a through 2f are diagrammatic views of stretch of track controlled by a system embodying my invention showing the code assignments and signal aspects as an eastbound train moves through the stretch of track.

Figs. 3a through 3f are diagrammatic views of a stretch of track controlled by a system embodying my invention showing the code assignments and signal aspects as a westbound train moves through the stretch of track.

Similar reference characters refer to similar parts in each of the several drawings.

Referring now to the Figs. 1a and 1b, there is shown a stretch of single track railway made up of track rails 1 and 2. Adjoining the western end of the stretch is a western passing siding W; adjoining the eastern end of the stretch is an eastern passing siding E. The stretch of single track is divided into track sections 2-3T, 4-5T and 6-7T by insulated joints 3 placed in the rails. At the western passing siding W, there is provided a station entering signal 1S and a station leaving signal 2S. Each of the signals governing traffic movement into and through the stretch may be of any suitable type, and are here shown as the well known color light type of signal. The control circuits for signal 1S form no part of my invention and are omitted. Signal 2S is controlled by a relay 2DR which in turn is

supplied energy from a decoding unit 180DU. The decoding unit 180DU is of a design well known in the art of railway signaling and will supply sufficient energy to relay 2DR to cause it to pick up when and only when the decoding unit is supplied with energy coded at a 180 code rate. The decoding unit is in turn controlled by a track relay 2TR through a decoding transformer 2TT. A reverse code transmitting relay 2RCR controls the supply of energy from a track battery 2TB to the track section 2-3T. The polarity of the energy supplied to section 2-3T is controlled by a relay 1DP which is in turn controlled jointly by the relay 2DR and a relay 1GP. The circuit controlling relay 1GP forms no part of my invention and it will suffice to say that relay 1GP will be energized when signal 1S indicates other than stop.

At the intermediate signal location A, two track relays 3DTR and 3HTR are at times connected in series across the rails of section 2-3T. These track relays are of the biased type, having contacts which are picked up when and only when current flows through the relay winding in the direction indicated by the arrow thereon. As can be seen in the Fig. 1a, relays 3DTR and 3HTR are responsive to currents of opposite polarity. Relay 3DTR controls a front contact repeater relay 3DTP and relay 3HTR controls a front contact repeater relay 3HTP. These four relays jointly control a signal control relay 3HR which, in turn, controls a signal 3S in conjunction with relay 3DTP.

Two coders 75CT and 180CT are also provided at location A. These coders may be of any of the several types well known in the art of railway signaling and are arranged so that coder 75CT will continuously operate its contacts at a 75 code rate while coder 180CT will continuously operate its contacts at a 180 code rate. A magnetic stick relay 4BCR is also provided at the intermediate signal location A. This type of relay is well known in the art and has the characteristic of operating its contacts in accordance with the direction of the flow of current through its winding and holding its contacts in the position to which they were last energized. As shown and described, a magnetic stick relay will operate its contacts in a direction opposite to the direction of current flow through its winding.

Furthermore, at intermediate signal location A, a biased track relay 4TR associated with the track section 4-5T, is also provided. A front contact repeater relay 4TFP is controlled by relay 4TR and these two relays jointly control a signal control relay 4HR. Relay 4HR in turn controls a signal 4S. Furthermore, in conjunction with several other relays, relay 4HR controls the code rate at which a code transmitting relay 3CTP codes energy supplied from a battery 3TB to the track section 2-3T. Another code transmitting relay 4ACR, which codes energy supplied to section 4-5T from a track battery 4TB, will be seen to be controlled by signal control relay 3HR as well as several other relays.

At intermediate signal location C, a biased track relay 5TR is provided which relay is responsive to the code transmitted by code transmitting relay 4ACR over the rails of section 4-5T. Relay 5TR controls the operation of a front contact repeater relay 5TFP and these two relays jointly control the operation of a signal control relay 5HR. Relay 5HR controls a signal 5S in a manner to be described subsequently.

Also found at intermediate signal location C are coders 75CT and 180CT which operate their contacts at code rates of 75 operations per minute and 180 operations per minute, respectively.

5 Also provided at intermediate signal location C is a code transmitting relay 5ACR and a magnetic stick relay 5BCR.

At intermediate location C, a pair of track relays 6DTR and 6HTR, of the biased type, connected in series and responsive to currents of opposite polarity are provided. Relay 6DTR controls the operation of a front contact repeater relay 6DTP and relay 6HTR controls the operation of front contact repeater relay 6HTP. 15 These four relays control the operation of a signal control relay 6HR, which in turn controls the operation of signal 6S. A code transmitting relay 6CTP will code energy supplied from a track battery 6TB to track section 6-7T.

20 At the eastern headblock location E, a track relay 7TR, of the biased type, will respond to energy coded by code transmitting relay 6CTP and supplied over the rails of section 6-7T. Relay 7TR governs the supply of energy to a decoding

25 transformer 7TT which in turn supplies energy to decoding unit 180DU. The decoding unit 180DU controls the supply of energy to a relay 7DR, which in turn controls a signal 7S. Relay 7DR and a relay 8GP, the control circuits for which 30 are not shown, jointly control a pole changing relay 8DP. A reverse code transmitting relay 7RCR is controlled by the track relay 7TR.

At each location, energy for the operation of the operation of the apparatus other than the 35 track circuits is furnished by a suitable source, such as the batteries LB, as shown, the positive and negative terminals of which are designated by the reference characters B and N, respectively.

As shown, the system is in the condition it 40 normally assumes when the stretch of track is unoccupied. The coders 75CT and 180CT located at intermediate signal locations A and C are continuously operating their contacts at their respective code rates due to the fact that all four

45 coders are continuously energized by obvious energizing circuits. At location A, for reasons which will be made clear presently, relay 3DTR is released and relay 3HTR is operating its contacts at a code rate of 180 times per minute. 50 For reasons which will be made clear subsequently, signal control relay 4HR is picked up. Accordingly, energy will be supplied to code transmitting relay 3CTP over a circuit which may be traced from positive terminal B of battery LB,

55 over back contact b of relay 3HTR when the contacts of that relay are released, back contact b of relay 3DTR, front contact b of coder 180CT which is operating at a 180 code rate, front contact b of relay 4HR, and the winding of relay 3CTP to negative terminal N of battery LB. Accordingly, relay 3CTP will operate its contact a at a 180 code rate. When front contact a of relay 3CTP is closed, energy will be supplied from track battery 3TB to track relay 2TR by

60 a track circuit which may be traced from the positive terminal of battery 3TB, over front contact a of relay 3CTP, the rail 2, the winding of track relay 2TR, back contact b of relay 2RCR and the rail 1 to the negative terminal of battery 3TB. When relay 2TR picks up, a stick circuit including front contact b of relay 2TR is established, and relay 2TR will remain picked up for the duration of the code impulse, after which it will release. Accordingly, relay 2TR will operate at a 180 code rate.

65 70 75

With relay 2TR operating its contacts at a 180 code rate, energy will be supplied to decoding transformer 2TT over contact *a* of relay 2TR at a 180 code rate. Accordingly, sufficient energy will be supplied through decoding unit 180DU to relay 2DR to cause the contacts of relay 2DR to pick up. Therefore, signal 2S will display a clear aspect due to the energization of its green lamp G over a circuit which may be traced from positive terminal B of battery LB; over front contact *a* of relay 2DR, and the green lamp G of signal 2S to negative terminal N of battery LB. With relay 2DR picked up the energizing circuit for relay 1DP, which circuit may be traced from positive terminal B of battery LB, over front contact *a* of relay 1GP, back contact *b* of relay 2DR, and the winding of relay 1DP to negative terminal N of battery LB, will be open at back contact *b* of relay 2DR. In this manner relay 1DP will be released, which is the condition in which it was described previously.

When the contacts of relay 2TR are picked up an energizing circuit for relay 2RCR will be established which may be traced from positive terminal B of battery LB, over contact *a* of relay 2TR, and the winding of relay 2RCR to negative terminal N of battery LB. Accordingly, relay 2RCR will be picked up when relay 2TR is picked up. During the off time of the code being supplied by relay 3TCP, relay 2TR will release and thereby deenergize relay 2RCR. However, relay 2RCR has a slightly slow release characteristic due to the fact that a snubbing circuit for that relay will be closed upon the release of relay 2TR. This snubbing circuit is obvious from an inspection of Fig. 1a and includes back contact *a* of relay 2TR. When relay 2TR is released and relay 2RCR remains picked up due to its slow release characteristic, energy will be supplied to track relays 3DTR and 3HTR from battery 2TB by a circuit which may be traced from the positive terminal of battery 2TB, over back contact *b* of relay 1DP, front contact *a* of relay 2RCR, back contact *b* of relay 2TR, the rail 1, the windings of relays 3HTR and 3DTR, back contact *a* of relay 3TCP, the rail 2, and back contact *a* of relay 1DP to the negative terminal of battery 2TB. It will be seen that this pulse of energy will be supplied to the section 2-3T for a relatively short period of time thereby conserving battery 2TB. The impulse of energy transmitted by relay 2RCR will be sufficient to operate the contacts of relay 3HTR which, due to its bias, will respond to energy of the polarity now being supplied from battery 2TB. Accordingly, relay 3HTR will operate its contacts at a 180 code rate.

At intermediate signal location A, with relay 3HTR operating its contacts at the 180 code rate and relay 3DTR having its contacts released, energy will be supplied to relay 3HTFP over a circuit which may be traced from positive terminal B of battery LB, over back contact *a* of relay 3DTR, front contact *a* or relay 3HTR which is operating at a 180 code rate, and the winding of relay 3HTFP to negative terminal N of battery LB. Accordingly, relay 3HTFP will be energized 180 times per minute. Relay 3HTFP is provided with a sufficiently slow release characteristic to remain picked up during the off time of the energy being supplied to it over its previously traced energizing circuit and, accordingly, relay 3HTFP will remain picked up as long as the system remains in the condition which is now being described. An energizing circuit for relay 3HR will also be established under these condi-

tions. This circuit may be traced from positive terminal B of battery LB, over back contact *a* of relay 3DTR, back contact *a* of relay 3HTR which is operating at a 180 code rate, front contact *a* of relay 3HTFP, and the winding of relay 3HR to negative terminal N of battery LB. Accordingly, relay 3HR will be energized 180 times per minute. Relay 3HR is provided with a sufficiently slow release characteristic to remain picked up during the off time of the energy being supplied to its winding and, accordingly, relay 3HR will remain picked up. It can be seen at this time that signal 3S will display its approach aspect due to the energization of its yellow lamp Y by a circuit which may be traced from positive terminal B of battery LB, over front contact *b* of relay 3HR, back contact *b* of relay 3HTFP, and the yellow lamp Y of signal 3S to negative terminal N of battery LB.

At intermediate signal location C, it will be subsequently shown that relay 6HTR is operating its contacts and relay 6DTR is released. It will also be shown presently that relay 5HR is energized and its contacts are picked up. With these relays in this condition and with coder 180CT operating continuously at a 180 code rate, it will be seen that relay 6CTP will be energized at a code rate of 180 times per minute by a circuit which may be traced from positive terminal B of battery LB, over back contact *b* of relay 6HTR when the contacts of that relay are released, back contact *b* of relay 6DTR, front contact *a* of coder 180CT which is operating at a 180 code rate, front contact *a* of relay 5HR, and the winding of relay 6CTP to negative terminal N of battery LB. Therefore, relay 6CTP will operate its contact *a* at a 180 code rate. Accordingly, track relay 7TR will be energized at a 180 code rate by energy supplied from track battery 6TB over a circuit which may be traced from the positive terminal of battery 6TB, over front contact *a* of relay 6CTP, rail 2 in section 6-7T, the winding of relay 7TR, back contact *a* of relay 7RCR, and rail 1 in section 6-7T to the negative terminal of battery 6TB. Each time relay 7TR picks up, it establishes a stick circuit for itself including front contact *b* of relay 7TR. At the end of each code pulse, relay 7TR releases its contacts. Accordingly, at this time relay 7TR will operate its contacts at a 180 code rate and thereby supply energy to the decoding transformer 7TT at a 180 code rate. Therefore, decoding unit 180DU will supply sufficient energy to keep relay 7DR picked up. With relay 7DR picked up, energy will be supplied to the green lamp G of signal 7S, so that it will show a clear aspect, over a circuit which may be traced from positive terminal B of battery LB, over front contact *a* of relay 7DR, and the green lamp G of signal 7S to negative terminal N of battery LB. With relay 7DR picked up the energizing circuit for relay 8DP, which will be subsequently traced, will be open at back contact *b* of relay 7DR and relay 8DP will be released.

When relay 7TR is picked up, an obvious energizing circuit for relay 7RCR including front contact *a* of relay 7TR will be established and, accordingly, relay 7RCR will pick up. During the off time of the code supplied from battery 6TB to relay 7TR, relay 7TR will release and open the energizing circuit for relay 7RCR at front contact *a* of relay 7TR. However, a snubbing circuit will be established for relay 7RCR over back contact *a* of relay 7TR and relay 7RCR will not immediately release. During the time

that relay 7TR is released but relay 7RCR remains picked up, energy will be supplied from track battery 7TB to the track relays 6DTR and 6HTR over a circuit which may be traced from the positive terminal of battery 7TB, over back contact *a* of relay 8DP, front contact *b* of relay 7RCR, back contact *b* of relay 7TR, rail 1 in section 6-7T, the windings of relays 6DTR and 6HTR, back contact *a* of relay 6CTP, rail 2 in section 6-7T, and back contact *b* of relay 8DP to the negative terminal of battery 7TB. It will be seen that relay 7RCR will be picked up and relay 7TR will be released only for a very short time during a code cycle. Accordingly, relatively little energy will be supplied from battery 7TB to track relays 6DTR and 6HTR, thereby conserving battery 7TB.

With the relay 7RCR supplying energy to the section 6-7T at a 180 code rate, and the energy being of such polarity that the current will flow through relay 6HTR in the direction necessary for it to operate its contacts, but not in the direction for relay 6DTR to operate its contacts, it will be seen that relay 6HTR will operate its contacts at a 180 code rate and relay 6DTR will be released. Accordingly, relay 6HTFP will be energized by a circuit which may be traced from positive terminal B of battery LB, over back contact *a* of relay 6DTR, front contact *a* of relay 6HTR which is operating at a 180 code rate, and the winding of relay 6HTFP to negative terminal N of battery LB. Relay 6HTFP is provided with a slow release characteristic so that it will remain picked up during the off time of the operation of relay 6HTR. Accordingly, relay 6HTFP will be picked up. With relay 6HTR operating in the manner already described and relay 6HTFP picked up, it will be seen that relay 6HR will be energized by a circuit which may be traced from positive terminal B of battery LB, over back contact *a* of relay 6DTR, back contact *a* of relay 6HTR, front contact *a* of relay 6HTFP, and the winding of relay 6HR to negative terminal N of battery LB. With relay 6DTR released, the energizing circuit for relay 6DTP, which will be traced subsequently, will be open at front contact *a* of relay 6DTR and relay 6DTP will be released. With the relay 6HR picked up and relay 6DTP released, it will be seen that signal 6S will display its approach aspect due to the energization of its yellow lamp Y by a circuit which may be traced from positive terminal B of battery LB, over front contact *b* of relay 6HR, back contact *b* of relay 6DTP, the yellow lamp Y of signal 6S to negative terminal N of battery LB.

At intermediate signal location C, let it be assumed that the contacts of relay 5BCR are in their normal or left-hand position and the contacts of track relay 5TR are released. Accordingly, when the contacts of coder 75CT are released an energizing circuit will be established for relay 5ACR which circuit may be traced from positive terminal B of battery LB, over front contact *a* of relay 6HR, back contact *b* of relay 5TR, normal contact *c* of relay 5BCR, back contact *b* of coder 75CT, and the winding of relay 5ACR to negative terminal N of battery LB. Accordingly, relay 5ACR will pick up and thereby establish a stick circuit for maintaining itself energized when coder 75CT picks up its contacts and opens the previously traced energizing circuit for relay 5ACR. This stick circuit for relay 5ACR may be traced from positive terminal B of battery LB, over front contact *a*

of relay 6HR, back contact *b* of relay 5TR, normal contact *c* of relay 5BCR, front contact *c* of relay 5ACR, and the winding of relay 5ACR to negative terminal N of battery LB. With relay 5ACR picked up, upon the picking up of coder 75CT, an energizing circuit will be established for energizing relay 5BCR so that the position of its contacts will become reversed. This circuit may be traced from positive terminal B of battery LB, over front contact *b* of relay 5ACR, front contact *a* of coder 75CT, the winding of relay 5BCR from right to left, and normal contact *a* of relay 5BCR to negative terminal N of battery LB. Accordingly, relay 5BCR will operate its contacts to their reverse position. The reversal of contact *c* of relay 5BCR opens the previously traced pick up and stick circuit for relay 5ACR but relay 5ACR remains energized at this time by a second stick circuit including front contact *a* of relay 6HR, back contact *b* of relay 5TR, front contact *b* of coder 75CT, and front contact *c* of relay 5ACR. Upon relay 5BCR reversing its contacts, a track circuit will become established for supplying energy from track battery 5TB to track relay 4TR. This circuit may be traced from the positive terminal of battery 5TB, over reverse contact *b* of relay 5BCR, front contact *a* of relay 5ACR, rail 1 in section 4-5T, back contact *a* of relay 4ACR, the winding of relay 4TR, and rail 2 in section 4-5T to the negative terminal of battery 5TB. Accordingly, relay 4TR will pick up. When coder 75CT releases, the second stick circuit for relay 5ACR will become open at front contact *b* of coder 75CT and accordingly relay 5ACR will release. The release of coder 75CT will also open the energizing circuit for relay 5BCR. However, the contacts of relay 5BCR will remain in their reverse position due to the magnetic stick characteristic of relay 5BCR. Upon coder 75CT again picking up, a circuit for energizing relay 5BCR so that its contacts will operate to their normal position will become established. This energizing circuit may be traced from positive terminal B of battery LB, over reverse contact *a* of relay 5BCR, the winding of relay 5BCR from left to right, front contact *a* of relay 75CT, and back contact *b* of relay 5ACR to negative terminal N of battery LB. Accordingly, relay 5BCR will operate its contacts to their normal position. In this manner it can be seen that energy will be supplied to the rails of section 4-5T from track battery 5TB when and only when relay 5ACR is picked up and relay 5BCR is in its reverse position. From the above description, it should be clear that this condition will occur during only one-half cycle of the operation of the coder 75CT out of two cycles of operation of that coder. Therefore, code will be supplied at a rate of thirty-seven and one-half times per minute with the "on" time of that code being one-fourth of the total time for the thirty-seven and one-half code cycle. In this manner appreciable energy will be saved since the drain on track battery 5TB will be one-half of the drainage which would occur if section 4-5T was energized at a 75 code rate.

In the above described manner it will be seen that track relay 4TR will be responding to energy being coded at a thirty-seven and one-half code rate and in this manner will supply energy to relay 4TFP at a thirty-seven and one-half code rate over a circuit which may be traced from positive terminal B of battery LB, over front contact *a* of relay 4TR which is operating at a

thirty-seven and one-half code rate, and the winding of relay 4TFP to negative terminal N of battery LB. Relay 4TFP has a sufficiently slow release characteristic so that it will not release during the off time of the thirty-seven and one-half code. Accordingly, with relay 4TR so operating, relay 4TFP will remain picked up. Furthermore signal control relay 4HR will be energized at a thirty-seven and one-half code rate over a circuit which may be traced from positive terminal B of battery LB, over back contact *a* of relay 4TR, front contact *a* of relay 4TFP, and the winding of relay 4HR to negative terminal N of battery LB. Relay 4HR is also provided with a slow release characteristic sufficient to maintain it picked up during the off time of the supply of energy to that relay. Accordingly, relay 4HR will be picked up at this time. With relay 4HR picked up, energy will be supplied to the green lamp G of signal 4S so that it will display a clear aspect by a circuit which may be traced from positive terminal B of battery LB, over front contact *c* of relay 4HR, and the green lamp G of signal 4S to negative terminal N of battery LB.

Each time relay 4TR picks up, a circuit will be established for a charging capacitor Q and this circuit may be traced from positive terminal B of battery LB, over front contact *b* of relay 4TR, front contact *b* of relay 4TFP, resistor R, and capacitor Q to negative terminal N of battery LB. Upon the release of relay 4TR, a circuit will be established for connecting capacitor Q across the winding of relay 4ACR and upon this circuit being established sufficient energy will be supplied from capacitor Q to the relay 4ACR to cause relay 4ACR to pick up its contact for a short period of time. This circuit connecting the capacitor Q across the winding of relay 4ACR may be traced from the right-hand terminal of the capacitor Q, through resistor R, front contact *b* of relay 4TFP, back contact *b* of relay 4TR, front contact *a* of relay 3HR, and the winding of relay 4ACR to the left-hand terminal of capacitor Q. Accordingly, relay 4ACR will pick up its contacts and establish a circuit for supplying energy from track battery 4TB to track relay 5TR which circuit may be traced from the positive terminal of battery 4TB, over front contact *a* of relay 4ACR, rail 1 in track section 4-5T, back contact *a* of relay 5ACR, the winding of relay 5TR, and rail 2 in track section 4-5T to the negative terminal of battery 4TB. It will be seen that relay 4ACR will be energized at the same code rate that track relay 4TR is being energized, that is, thirty-seven and one-half times per minute. Accordingly, relay 5TR will be energized at this same thirty-seven and one-half code rate. In this manner the drain on battery 4TB is kept to minimum during this normal unoccupied condition. It should be pointed out that resistor R is included in these circuits in order to limit current flow and reduce contact arcing.

As was already stated, the "on" time of the normal thirty-seven and one-half code is approximately 25% of the total time for a thirty-seven and one-half code cycle. Capacitor Q and relay 4ACR are so proportioned that the "on" time of the reverse thirty-seven and one-half code is less than 25% of the thirty-seven and one-half code cycle so that the total "on" time of the normal and reverse thirty-seven and one-half codes is less than 50% of the time for a thirty-seven and one-half code cycle. With such a short total "on" time, the well known track storage current effect

will be minimized. However, the "on" time of the normal and reverse thirty-seven and one-half codes are of sufficient duration to reliably feed through at least three front contact repeating cut sections, if needed, without excessive code distortion. This feature is of great benefit from an economic view-point, since the front contact repeating cut section, as is well known in the art of railway signaling, requires much less apparatus, is much simpler, and is less costly than any other type of coded track cut section or code generating location.

With relay 5TR operating at a thirty-seven and one-half code rate, relay 5TFP will be energized thirty-seven and one-half times per minute over a circuit including front contact *a* of relay 5TR. Relay 5TFP is provided with a sufficiently slow release characteristic to remain picked up during the off periods of its energization and, accordingly, with relay 5TR operating at a thirty-seven and one-half code rate, relay 5TFP will remain picked up. With relay 5TFP picked up, relay 5HR will be energized thirty-seven and one-half times per minute over a circuit which may be traced from positive terminal B of battery LB, over back contact *a* of relay 5TR which is operating at a thirty-seven and one-half code rate, front contact *a* of relay 5TFP, and the winding of relay 5HR to negative terminal N of battery LB. Relay 5HR has a sufficiently slow release characteristic to remain picked up during the "off" period of its energization. Accordingly, with relay 5TR operating at a thirty-seven and one-half code rate, relay 5HR will remain picked up. With relay 5HR energized, signal 5S will display a clear aspect due to the energization of its green lamp G by an obvious circuit including front contact *b* of relay 5HR. The code assignments for the several track sections and the aspect displayed by the various signals when the stretch is in its normal unoccupied condition is shown in Figs. 2a and 3a.

My system is so arranged that when a train occupies a particular section, regardless of the direction the train is moving, the code assignments and signal aspects will be the same. When a train occupies the western passing siding, signal 1S will display a stop or red aspect and relay 1GP will become released. This, however, will have no effect upon the remainder of the system since with the relay 1GP released, the circuit for energizing relay 1DP will merely become open at an additional point and therefore relay 1DP will remain released. Accordingly, the remainder of the system will maintain its original condition. Therefore, the system will assume the condition shown in Fig. 2b and Fig. 3f.

The condition the system assumes when a train occupies section 2-3T is shown in Figs. 2c and 3d. 60 When a train occupies section 2-3T, signal 1S will be clear and relay 1GP will be picked up. Any energy being supplied to section 2-3T will be shunted by the wheels and axles of the train, and accordingly, track relays 2TR, 3DTR and 3HTR will be released. As will subsequently be seen, energy at a 180 code rate will be supplied to section 2-3T by code transmitting relay 3CTP. With track relay 2TR released, code transmitting relay 2RCR will also be released. Therefore, no reverse code will be supplied to section 2-3T. Furthermore, with track relay 2TR released no coded energy will be supplied to decoding transformer 2TT and, accordingly, no energy will be supplied to the decoding unit 180DU. Therefore, relay 2DR will be released and establish an obvious circuit for en-

ergizing the red lamp R of signal 2S. With relay 2DR released, an energizing circuit will be established for supplying energy to relay 1DP, which circuit may be traced from positive terminal B of battery LB, over front contact *a* of relay 1GP, back contact *b* of relay 2DR, and the winding of relay 1DP to negative terminal N of battery LB. Accordingly, relay 1DP will be picked up but this will have no effect upon the circuit arrangement.

At intermediate signal location A, with track relays 3DTR and 3HTR both released, relays 3DTP, 3HTP, and 3HR will all be released. Upon the release of relay 3HR, an obvious circuit for energizing the red lamp R of signal 3S will become established, which circuit includes back contact *b* of relay 3HR.

With relay 3HR released, the previously traced circuit for discharging capacitor Q through the winding of relay 4ACR will be open at front contact *a* of relay 3HR. Accordingly, no energy will be supplied from the capacitor Q to relay 4ACR and that relay will be released. Therefore, no energy will be supplied from battery 4TB to track relay 5TR since that track circuit will be opened at front contact *a* of relay 4ACR. Accordingly, relay 5TR will be released and stay released. Therefore, at intermediate signal location C, relay 5TFP will be released since it is not being supplied with energy over front contact *a* of relay 5TR, and with relay 5TFP released, relay 5HR will be released and thereby establish a circuit for energizing red lamp R of signal 5S over back contact *b* of relay 5HR. The release of relays 5TR and 5HR will have no effect upon the generation of thirty-seven and one-half code as was explained at the end of the description of the system in its normal unoccupied condition. Accordingly, thirty-seven and one-half code will be transmitted from track battery 5TB to track relay 4TR over front contact *a* of code transmitting relay 5ACR and in this manner relay 4TR will operate as it did during the time the track stretch was unoccupied. Therefore, relays 4TFP and 4HR will be energized and picked up. Accordingly, signal 4S will display a clear aspect due to the energization of the green lamp G over front contact *c* of relay 4HR in a manner already described.

Furthermore, with relay 4HR picked up, energy at a 180 code rate will be supplied to relay 3CTP by a circuit which may be traced from positive terminal B of battery LB, over back contact *b* of relay 3HTR, back contact *b* of relay 3DTR, front contact *b* of coder 180CT which is operating at a 180 code rate, front contact *b* of relay 4HR, and the winding of relay 3CTP to negative terminal N of battery LB. Therefore, relay 3CTP will operate its contact at a 180 code rate to transmit 180 code to section 2-3T. Of course, as was described earlier, the code being transmitted to section 2-3T by relay 3CTP will be shunted by the wheels and axles of the train occupying the section.

With relay 5HR released, a circuit is established for supplying energy to code transmitting relay 6CTP which circuit may be traced from positive terminal B of battery LB, over front contact *c* of coder 15CT, back contact *a* of relay 5HR, and the winding of relay 6CTP to negative terminal N of battery LB. Accordingly, relay 6CTP will operate at a 75 code rate and supply energy to track relay 7TR over a track circuit which may be traced from the positive terminal of track battery 6TB, over front contact *a* of relay 6CTP which is operating at a 75 code rate, rail 2 in section 6-7T, through the winding of relay 7TR, back contact *a* of relay 1RCR, rail 1 in section 6-7T, to the nega-

tive terminal of track battery 6TB. Accordingly, relay 7TR will operate at a 75 code rate.

Because relay 7TR is operating at a 75 code rate, insufficient energy will be supplied from the decoding unit 180DU to relay 7DR to keep that relay picked up. Accordingly, relay 7DR will be released and thereby establish a circuit including back contact *a* of relay 7DR for energizing red lamp R of signal 7S. Furthermore, with relay 7DR released, relay 8DP will become energized by a circuit which may be traced from positive terminal B of battery LB, over front contact *a* of relay 8GP, back contact *b* of relay 7DR, and the winding of relay 8DP to negative terminal N of battery LB. In this manner the polarity of the reverse code being supplied from track battery 7TB to section 6-7T in a manner to be described below will be the reverse of the polarity of the code transmitted by relay 1RCR when the stretch is unoccupied.

Upon relay 7TR picking up during the "on" time of the code being supplied by code transmitting relay 6CTP, a circuit for energizing relay 1RCR will become established, which circuit includes front contact *a* of relay 7TR. During the "off" time of the code being supplied to relay 7TR, relay 7TR will release. Relay 1RCR will remain picked up for a short time due to its slow release characteristic. However, the slow release characteristic of relay 1RCR will not be sufficient to maintain it picked up until relay 7TR becomes reenergized and, accordingly, relay 1RCR will finally release. During the interval between the release of relay 7TR and the release of relay 1RCR, energy will be supplied from track battery 7TB to track relays 6DTR and 6HTR over a track circuit which may be traced from the positive terminal of track battery 7TB, over front contact *b* of relay 8DP, rail 2 in section 6-7T, back contact *a* of relay 6CTP, the windings of relay 6HTR and 6DTR, rail 1 in section 6-7T, back contact *b* of relay 7TR, front contact *b* of relay 1RCR, and front contact *a* of relay 8DP to the negative terminal of battery 7TB. It will be seen that the "on" time of this code being supplied from battery 7TB will be relatively short in comparison to its "off" time and, in this manner, appreciable saving in wear on battery 7TB may be achieved as well as a reduction in track storage current effect. It will also be seen that the code rate at which energy will be supplied from battery 7TB to track relays 6DTR and 6HTR will be at a 75 code rate.

With the reverse code being transmitted to section 6-7T now being of such polarity that rail 1 is negative and rail 2 positive, relay 6DTR will be operating at a 75 code rate and relay 6HTR will be released and remain released. Accordingly, relay 6HTFP will be released but relay 6DTP will now be energized 75 times per minute over front contact *a* of relay 6DTR. Relay 6DTP is provided with a sufficiently slow release characteristic to remain energized during the "off" time of the energy being supplied to it and, accordingly, relay 6DTP will pick up and stay picked up. Therefore, energy will be supplied to relay 6HR over a circuit which may be traced from positive terminal B of battery LB, over back contact *a* of relay 6DTR which is operating at a 75 code rate, back contact *a* of relay 6HTR, front contact *a* of relay 6DTP, and the winding of relay 6HR to negative terminal N of battery LB.

Accordingly, relay 6HR will remain picked up. With relay 6DTPF now picked up, it will be seen that energy will be supplied to the green lamp G of signal 6S over a circuit which may be traced from positive terminal B of battery LB, over front contact b of relay 6HR, front contact b of relay 6DTPF, and green lamp G of signal 6S to negative terminal N of battery LB.

The condition the system assumes when a train occupies section 4-5T is shown in Figs. 2d and 3d. When a train occupies section 4-5T, any energy being supplied to that section will be shunted by the wheels and axles of the train and track relays 4TR and 5TR will therefore be released. As will be shown subsequently, thirty-seven and one-half code is being supplied to section 4-5T at location C and ninety code is being supplied to section 4-5T at location A. With relay 4TR released, relay 4TFP and relay 4HR will be released. With relay 4HR released, an obvious circuit will be established for energizing the red lamp R of signal 4S. With relay 5TR released, relays 5TFP and 5HR will be released and, accordingly, an obvious energizing circuit will be established for the red lamp R of signal 5S.

With relay 4HR released, a circuit will be established for energizing relay 3CTP at a 75 code rate, which circuit may be traced from positive terminal B of battery LB, over front contact a of coder 75CT, back contact b of relay 4HR, and the winding of relay 3CTP to negative terminal N of battery LB. Accordingly, relay 3CTP will be energized 75 times per minute and will therefore code energy supplied from track battery 3TB to track relay 2TR at a 75 code rate. With relay 2TR being energized at a 75 code rate, decoding unit 180DU will not supply sufficient energy to relay 2DR to pick it up and, accordingly, it will remain released and maintain the circuit for energizing the red lamp R of signal 2S. Furthermore, with relay 2DR released, relay 1DP will remain energized and a reverse code of 75 pulses per minute will be transmitted from track battery 2TB to track relays 3DTR and 3HTR in a manner similar to that already described. With relay 1DP picked up, this reverse 75 code will be of such polarity that rail 1 will be energized negatively and rail 2 positively and, therefore, relay 3DTR will be operating at a 75 code rate and relay 3HTR will be released. Accordingly, relay 3HTFP will be released but relay 3DTPF will be energized over a circuit which may be traced from positive terminal B of battery LB, over front contact a of relay 3DTR which is operating at a 75 code rate, and the winding of relay 3DTPF to negative terminal N of battery LB. Relay 3DTPF is provided with a slow release characteristic so that it will remain picked up during the off time of the coded energy being supplied to it. Accordingly, relay 3DTPF will remain picked up and thereby establish an energizing circuit for relay 3HR which circuit may be traced from positive terminal B of battery LB, over back contact a of relay 3DTR which is operating at a 75 code rate, back-contact a of relay 3HTR, front contact a of relay 3DTPF, and the winding of relay 3HR to negative terminal N of battery LB. As was stated earlier, relay 3HR is provided with a sufficiently slow release characteristic to remain picked up during the off time of the energy being supplied to it. Accordingly, relay 3HR will remain picked up and establish an energizing circuit for the green lamp G of signal 3S which circuit may be traced from positive terminal B of battery LB, over front contact b of relay 3HTR, front contact b of relay 3DTPF, and green lamp G of signal 3S to negative terminal N of battery LB.

tact b of relay 3HR, front contact b of relay 3DTPF, and the green lamp G of signal 3S to negative terminal N of battery LB.

With relay 3HR energized, its contacts are picked up. Let it be assumed that relay 4ACR is released and relay 4BCR has its contacts in their reverse or right-hand position. Furthermore, let it be assumed that at this instant coder 180CT is released. Upon coder 180CT picking up a circuit will be established for energizing relay 4BCR so that it will operate its contacts to their normal position. This circuit may be traced from positive terminal B of battery LB, over reverse contact a of relay 4BCR, the winding of relay 4BCR from left to right, front contact a of coder 180CT, and back contact b of relay 4ACR to negative terminal N of battery LB. Accordingly, relay 4BCR will operate its contacts to their normal position. Upon the release of coder 180CT, the energizing circuit for relay 4BCR will become open at front contact a of coder 180CT, but the contacts of relay 4BCR will remain in their normal position due to the magnetic stick characteristic of relay 4BCR. Furthermore, when coder 180CT releases, a circuit will be established for energizing code transmitting relay 4ACR which circuit may be traced from positive terminal B of battery LB, over normal contact b of relay 4BCR, back contact b of coder 180CT, back contact b of relay 4TFP, back contact b of relay 4TR, front contact a of relay 3HR, and the winding of relay 4ACR to negative terminal N of battery LB. Accordingly, relay 4ACR will pick up and thereby establish a track circuit for supplying energy from track battery 4TB to track relay 5TR, which circuit may be traced from the positive terminal of battery 4TB over front contact a of relay 4ACR, rail 1 in section 4-5T, back contact a of relay 5ACR, the winding of relay 5TR, and rail 2 in section 4-5T to the negative terminal of battery 4TB. Upon the picking up of coder 180CT a second time, relay 4ACR will continue to be energized by a stick circuit which may be traced from positive terminal B of battery LB, over normal contact b of relay 4BCR, front contact c of relay 4ACR, back contact b of relay 4TFP, back contact b of relay 4TR, front contact a of relay 3HR, and the winding of relay 4ACR to negative terminal N of battery LB. Accordingly, relay 4ACR will continue to remain picked up and thereby provide a circuit for continuing the supply of energy to track relay 5TR from battery 4TB. Furthermore, upon the second picking up of coder 180CT, with relay 4ACR now stuck up, a circuit will be established for energizing relay 4BCR so that its contacts will operate to their reverse position. This circuit may be traced from positive terminal B of battery LB, over back contact a of relay 4HR, front contact b of relay 4ACR, front contact a of coder 180CT, the winding of relay 4BCR from right to left, and normal contact a of relay 4BCR to negative terminal N of battery LB. Accordingly, relay 4BCR will operate its contacts to their reverse position. However, relay 4ACR will not release because it will continue to remain energized by a second stick circuit which may be traced from positive terminal B of battery LB, over front contact b of coder 180CT, front contact c of relay 4ACR, back contact b of relay 4TFP, back contact b of relay 4TR, front contact a of relay 3HR and the winding of relay 4ACR to negative terminal N of battery LB. Upon coder 180CT releasing a second time, the second stick circuit for relay 4ACR will

become open at front contact *b* of coder 180CT, relay 4ACR will release and the cycle will be repeated. It will be seen from the above explanation that code transmitting relay 4ACR will remain picked up during a cycle of operation of coder 180CT and relay 4ACR will remain released during a cycle of operation of coder 180CT. Accordingly, the code transmitting relay 4ACR will be operating at a ninety code rate and transmitting energy to section 4-5T at that code rate. However, if, as supposed, a train is occupying section 4-5T, the wheels and axles of the train will shunt this energy.

With relay 5HR released, energy will be supplied to code transmitting relay 6CTP at a 75 code rate over a circuit which may be traced from positive terminal B of battery LB, over front contact *c* of coder 75CT, back contact *a* of relay 5HR, and the winding of relay 6CTP to negative terminal N of battery LB. Accordingly, energy will be supplied from track battery 6TB to track relay 7TR at a code rate of 75 times per minute over front contact *a* of relay 6CTP. Therefore, track relay 7TR will operate at a 75 code rate which will result in relay 1DR being released and the red lamp R of signal 1S being energized. Furthermore, code transmitting relay 7RCR will transmit a reverse code in a manner substantially the same as that already described when a train occupied section 2-3T and this energy will cause relay 6DTR to operate and relay 6HTR to remain released. Therefore, relays 6DTP and 6HR will be picked up. Accordingly, in a manner similar to that described when a train occupied section 2-3T, signal 6S will display a clear aspect.

With relay 6HR picked up, energy will be supplied to relays 5ACR and 5BCR in a manner already described and, accordingly, relay 5ACR will transmit thirty-seven and one-half code to section 4-5T. Of course, with a train in section 4-5T, this energy will be shunted by the wheels and axles of the train.

One of the main advantages of my system is utilizing opposing codes of different slow code rates. As was pointed out earlier, using a thirty-seven and one-half normal and reverse code with a total on time of less than 50% minimizes track storage current effect in track circuits, but still permits the use of several cut sections in section 4-5T. With a train occupying the section 4-5T, both thirty-seven and one-half and ninety codes are supplied so that upon the train vacating the section, the transmitting apparatus at both ends cannot get into synchronism but will reset in a relatively short time so that the system will operate in the prescribed manner.

Figs. 2e and 3c show the condition of the system when a train occupies section 6-7T. When a train occupies section 6-7T, any energy being transmitted to the track rails in that section will be shunted by the wheels and axles of the train and track relays 7TR, 6HTR and 6DTR will therefore be released. As will be shown presently, energy at a 180 code rate will be supplied to section 6-7T from location C. With relay 7TR released, no energy will be supplied to relay 7RCR and it too will be released. Accordingly, no reverse code will be supplied to section 6-7T. Furthermore, no energy will be supplied to decoding transformer 7TT and, accordingly, no energy will be supplied to relay 1DR. Therefore, relay 1DR will also be released and thereby establish a circuit for maintaining the red lamp R of signal 1S energized.

At signal location C, with track relays 6DTR

5

and 6HTR released, relays 6DTP, 6HTP and 6HR will all be released. Accordingly, a circuit will be established for energizing the red lamp R of signal 6S which circuit includes back contact *b* of relay 6HR.

With relay 6HR released, the previously traced energizing circuit for supplying energy to code transmitting relay 5ACR will be open at front contact *a* of relay 6HR. Accordingly, no energy will be supplied from track battery 5TB to the rails of track section 4-5T from the east end of the section. Therefore, at signal location A, track relay 4TR will be released. With relay 4TR released, no energy will be supplied to relay 4TFP over front contact *a* of relay 4TR, and relay 4TFP will be released. With relay 4TFP released, the previously traced energizing circuit for relay 4HR will be open at front contact *a* of relay 4TFP and relay 4HR will be released. Accordingly, the red lamp R of signal 4S will be energized over an obvious circuit.

With relay 4HR released, a circuit will be established for supplying coded energy at a 75 code rate to code transmitting relay 3CTP. This circuit may be traced from positive terminal B of battery LB, over front contact *a* of coder 75CT, back contact *b* of relay 4HR, and the winding of relay 3CTP to negative terminal N of the battery LB. Accordingly, relay 3CTP will operate its contacts at a 75 code rate and coded energy is thus supplied from track battery 3TB to track relay 2TR at a 75 code rate. Therefore, track relay 2TR will operate at a 75 code rate. With relay 2TR so operating, insufficient energy will be supplied to relay 2DR to cause it to pick up. Therefore, signal 2S will display a red aspect as previously described.

Furthermore, with relay 2TR operating at a 75 code rate, relay 2RCR will transmit a reverse code at a 75 code rate as was previously described. The polarity of the code being transmitted by relay 2RCR from battery 2TB will be such that rail 2 will be energized with energy of positive polarity and rail 1 with energy of negative polarity. Accordingly, at signal location A, relay 3DTR will operate and relay 3HTR will be released. Therefore, relay 3DTP will be picked up and relay 3HR will also be picked up. With relay 3HR picked up and relay 3DTP picked up, the circuit for energizing the green lamp G of signal 3S, which has already been traced, will remain closed.

Furthermore, with relay 3HR picked up, the previously traced circuits for controlling relays 4ACR and 4BCR will be established and relay 4ACR will transmit ninety code in a manner already described. Therefore, at location C, relay 5TR will commence operating at a ninety code rate and thereby energize relay 5TFP ninety times per minute over an obvious circuit including front contact *a* of relay 5TR. Because of the slow release characteristic of relay 5TFP, it will remain picked up during the off time of its energization. Accordingly, in a manner already described, relay 5HR will pick up and establish an obvious energizing circuit for green lamp G of signal 5S.

With relay 5HR picked up, the previously traced energizing circuit for supplying energy to relay 6CTP at a 75 code rate will be established. Accordingly, relay 6CTP will transmit 75 code to section 6-7T but, of course, with a train occupying the section, this energy will be shunted by the wheels and axles of the train.

75

When a train occupies the eastern passing

siding E signal 8S will display its stop or red aspect and relay 8GP will be released. Therefore, the previously traced energizing circuit for relay 8DP will be open at front contact *a* of relay 8GP and, accordingly, relay 8DP will be released. Furthermore, with a train in the eastern passing siding E, 180 code will be transmitted by relay 6CTP in a manner identical to that described for the normal condition and will be received by track relay 7TR, which will operate in a 180 code rate. Accordingly, relay 7RCR will operate at 180 code rate and transmit a reverse 180 code of polarity such that rail 2 is energized with energy of negative polarity and rail 1 is energized with energy of positive polarity, in a manner substantially the same as described for the normal unoccupied condition. Therefore, relay 6HTR will operate at a 180 code rate and relay 6DTR will remain released. Accordingly, signal 6S will display its yellow aspect as previously described. With relay 6HTR operating, relay 6HR will once more pick up and enable relay 5ACR to transmit thirty-seven and one-half code as already described. Therefore, at location A, relay 4TR will operate at a thirty-seven and one-half code rate, and in a manner substantially like that described for the normal condition, relay 4ACR will transmit a reverse thirty-seven and one-half code to track relay 5TR. With relay 4TR so operating, relay 4HR will be picked up and thereby establish a circuit for energizing relay 3CTP 180 times per minute. Accordingly, relay 3CTP will transmit 180 code to relay 2TR which will operate its contacts 180 times per minute. Relay 2RCR will operate its contacts 180 times per minute and thereby transmit a reverse code, with rail 1 energized positively and rail 2 energized negatively, to relay 3HTR. It can be seen from the description that when a train occupies the eastern passing siding E, the system is in its normal condition with the exception of signal 8S which will indicate stop. The signal aspects and code assignments for the system when a train occupies eastern passing siding E are shown in Figs. 2f and 3b.

Having described the operation of my novel system when a train, traveling either eastbound or westbound, occupies the various sections in the stretch, let it now be assumed that a train approaches the stretch of track moving in an eastbound direction. When the train is in the western passing siding W and approaches the stretch of single track, signal 1S will display a stop or red aspect and relay 1DP will become released. This, however, will have no effect upon the remainder of the system since, with relay 1DP released, the circuit for energizing relay 1DP will become open at an additional point and therefore relay 1DP will remain released. Accordingly, the remainder of the system will remain in its original condition. The various code assignments and signal aspects when a train traveling in an eastbound direction occupies the western passing W are shown in Fig. 2b.

When an eastbound train enters section 2-3T, and leaves the western passing siding W, signal 1S will clear up and relay 1GP will pick up and both will stay in this condition for the remainder of the eastbound movement, assuming a following eastbound train does not occupy the western 70 passing siding W. With a train in section 2-3T, any energy being supplied to that section will be shunted by the wheels and axles of the train and, accordingly, relays 2TR, 3DTR and 3HTR will release. Therefore, relays 3DTP and

3HTFP will release, as will relay 3HR. Accordingly, signal 3S will display its red aspect. Furthermore, with relay 3HR released, the previously traced energizing circuit for relay 4ACR will become open at front contact *a* of relay 3HR and relay 4ACR will release. Therefore, no energy will be supplied to section 4-5T over front contact *a* of relay 4ACR and, accordingly, relay 5TR will release. 10 With relay 5TR released, relays 5TFP and 5HR will become deenergized and they too will release. With relay 5HR released, signal 5S will display a red aspect. Furthermore, with relay 5HR released, an energizing circuit for supplying 75 code to code transmitting relay 6CTP will become established which circuit may be traced from positive terminal B of battery LB, over front contact *c* of coder 75CT, back contact *a* of relay 5HR, and the winding of relay 6CTP to negative terminal N of battery LB. Accordingly, relay 6CTP will commence operating its contact at a 75 code rate and transmit energy at that code rate from battery 6TB to track relay 7TR. In the manner already described, with relay 7TR 20 operating at a 75 code rate, relay 7RCR will also operate at a 75 code rate and these two relays together will generate and transmit a 75 reverse code to section 6-7T. Because relay 7TR is operating at a 75 code rate, insufficient energy will 25 be supplied to relay 7DR to keep it picked up and it will be released. Therefore, signal 7S will display its red aspect. Furthermore, with relay 7DR released, relay 8DP will become energized by a circuit which may be traced from positive terminal B of battery LB, over front contact *a* of relay 8GP, back contact *b* of relay 7DR, and the winding of relay 8DP to negative terminal N of battery LB. Accordingly, relay 8DP will pick up, thereby causing the reverse 75 code 30 being transmitted to section 6-7T by relay 7RCR to be of such polarity that rail 2 will be energized positively and rail 1 energized negatively. 35

With section 6-7T being so energized, relay 6DTR will commence operating at a 75 code rate 40 and relay 6HTR will release. Accordingly, in a manner already described, relay 6DTP will become picked up and relay 6HR will remain energized. Therefore, signal 6S will display a green aspect due to energization of its green lamp G 45 by a circuit including front contact *b* of relay 6HR and front contact *b* of relay 6DTP.

With relay 6HR picked up, relays 5ACR and 5BCR will continue to be energized in such a manner as to generate thirty-seven and one-half 50 code and transmit that code to section 4-5T. A detailed description of the generation and transmission of thirty-seven and one-half code at signal location C has previously been made. Accordingly, at signal location A, track relay 4TR will continue operating its contacts at a thirty-seven and one-half code rate and, in a manner already described, relays 4TFP and 4HR will remain picked up. With relay 4HR picked up, signal 4S will display a green aspect due to the 55 energization of its green lamp G by an obvious circuit including front contact *c* of relay 4HR. Furthermore, with relay 4HR picked up, code transmitting relay 3CTP will be energized 180 times per minute by a circuit which may be traced from positive terminal B of battery LB, over back contact *b* of relay 3DTR, front contact *b* of coder 180CT which is operating at a 180 code rate, front contact *b* of relay 4HR, and the winding 60 of relay 3CTP to negative terminal N of battery 65

LB. Accordingly, relay 3CTP will code energy being supplied from track battery 3TB to section 2-3T by its front contact *a* at a 180 code rate. However, with a train occupying section 2-3T, the energy being coded by relay 3CTP will be shunted by the wheels and axles of the train and, therefore, relay 2TR will be released. With relay 2TR released, relay 2RCR will be released and no reverse code will be transmitted to section 2-3T. Furthermore, with relay 2TR released, relay 2DR will be released, and signal 2S will therefore display its red aspect. The code assignments and signal aspects in my system when an eastbound train occupies section 2-3T are shown in Fig. 2c.

When the eastbound train vacates section 2-3T and occupies section 4-5T, any energy being supplied to section 4-5T will be shunted by the wheels and axles of the train and, accordingly, relay 4TR will release and relay 5TR will remain released. With relay 4TR released, relays 4TFP and 4HR will release and thereby establish a circuit for energizing the red lamp R of signal 4S, which circuit includes back contact *c* of relay 4HR. Furthermore, with relay 4HR now released, relay 3CTP will commence being energized at a 75 code rate by a circuit which may be traced from positive terminal B of battery LB, over front contact *a* of coder 75CT which is operating at the 75 code rate, back contact *b* of relay 4HR, and the winding of relay 3CTP to negative terminal N of battery LB. Accordingly, relay 3CTP will code energy supplied from track battery 3TB to track relay 2TR in a manner already described and relays 2TR and 2RCR will commence operating at a 75 code rate. As was explained earlier, with relay 2TR operating at a 75 code rate, relay 2DR will be released and signal 2S will display a red aspect. As was stated earlier, signal 1S is displaying its clear aspect and relay 1GP is picked up. With relay 2DR released, a circuit will be established for energizing relay 1DP, which circuit may be traced from positive terminal B of battery LB, over front contact *a* of relay 1GP, back contact *b* of relay 2DR, and the winding of relay 1DP to negative terminal N of battery LB. Accordingly, relay 1DP will pick up and establish a circuit so that the reverse code being supplied to section 2-3T will be of such polarity that rail 2 will be energized positively and rail 1 will be energized negatively. Therefore, at signal location A, relay 3DTR will commence operating and relay 3HTR will remain released. Accordingly, relay 3DTFP will pick up and establish an energizing circuit for relay 3HR which will also pick up. Therefore signal 3S will display its green aspect due to energization of the green lamp G by a circuit including front contact *b* of relay 3HR and front contact *b* of relay 3DTFP.

With relay 3HR now picked up, relays 4ACR and 4BCR will commence operating in a manner already described to generate and transmit 90 code to section 4-5T. However, with the train now occupying section 4-5T, this energy will be shunted by the wheels and axles of the train and, accordingly, relay 5TR will remain released. Therefore, relays 5TFP and 5HR will remain released and signal 5S will continue to display its red aspect. Furthermore, with relay 5HR still released, relay 6CTP will continue to be energized at a 75 code rate, as was previously described, and relays 1TR and 1RCR will continue to operate at a 75 code rate and transmit a reverse code to section 6-7T with rail 2 energized positively and rail 1 energized negatively.

Therefore, at the eastern passing siding E, relay 7DR will remain released and signal 7S will continue displaying its red aspect.

At signal location C, relay 6DTR will continue to operate at a 75 code rate and relay 6HTR will remain released. Therefore, signal 6DTFP will remain picked up, relay 6HTFP will remain released and relay 6HR will remain energized. Therefore, signal 6S will continue to display its green aspect. Furthermore, with relay 6HR picked up, relays 5BCR and 5ACR will continue to operate in a manner already described so that they will cooperate to generate and transmit thirty-seven and one-half code to section 4-5T. However, this energy will be shunted by the wheels and axles of the train now occupying section 4-5T and, as was already described, relay 4TR will remain released. It should be noted, as the train vacates section 4-5T, the 90 code and the thirty-seven and one-half code will scramble, and because of the different code rates the system will reset itself so that it will continue to operate in the prescribed manner in a relatively short time. If the codes were at the same code rate, it would be possible for the code transmitters at both ends of section 4-5T to get into synchronism in which condition they might remain for an extended period of time. If this were the case, the remaining portions of the system would not function properly for an extended period of time. The code assignments and signal aspects in my system when an eastbound train occupies section 4-5T are shown in Fig. 2d.

When the eastbound train vacates section 4-5T and occupies section 6-7T, any energy being supplied to section 6-7T will be shunted by the wheels and axles of the train and, accordingly, relays 7TR, 6DTR and 6HTR will all be released. Therefore, relays 6DTFP and 6HR will release and signal 6S will display its red aspect. Furthermore, with relay 6HR released, no energy will be supplied to operate relays 5ACR and 5BCR in the manner already described for generating and transmitting thirty-seven and one-half code and, accordingly, no energy will be supplied to section 4-5T at signal location C.

Accordingly, at signal location A, relays 4TR, 4TFP and 4HR will remain released and signal 4S will continue to display its red aspect. With relay 4HR released, relay 3CTP will continue to code energy at a 75 code rate to section 2-3T and relays 2TR and 2RCR will continue to operate at a 75 code rate and transmit a reverse code to section 2-3T of such polarity that rail 2 is energized positively and rail 1 is energized negatively. Furthermore, signal 2S will continue to display its red aspect due to the fact that relay 2DR will remain released.

Therefore, at signal location A, relay 3DTR will continue to operate at a 75 code rate and relay 3HTR will remain released. Accordingly, relay 3DTFP will remain energized and relay 3HR will remain picked up. Therefore signal 3S will continue to display its green aspect. Furthermore, with relay 3HR remaining picked up, relay 4ACR will continue to transmit 90 code to section 4-5T in a manner already described. Therefore, at location C, relay 5TR will commence to operate at a 90 code rate and relays 5TFP and 5HR will pick up. Therefore, signal 5S will now display a green aspect. Furthermore, with relay 5HR now picked up, relay 6CTP will commence to be energized at a 180 code rate by a circuit which may be traced from positive

terminal B of battery LB, over back contact b of relay 6HTR, back contact b of relay 6DTR, front contact a of coder 180CT which is operating at a 180 code rate, front contact a of relay 5HR, and the winding of relay 6CTP to negative terminal N of battery LB. Accordingly, relay 6CTP will commence transmitting 180 code to section 6-7T and, as long as the train occupies section 6-7T, this energy will be shunted by the wheels and axles of that train. The code assignments and signal aspects in my system when an eastbound train occupies section 6-7T are shown in Fig. 2c.

However, when the eastbound train enters the eastern passing siding and vacates section 6-7T, the 180 code being transmitted to section 6-7T will commence energizing relay 7TR. Therefore, relays 7TR and 7RCR will commence operating at a 180 code rate. Furthermore, relay 7DR will now pick up and signal 7S will commence displaying a green aspect. Upon the picking up of relay 7DR, the energizing circuit for relay 8DP will become open at back contact b of relay 7DR and relay 8DP will release. Therefore, the reverse code being transmitted by relay 7RCR will now be of such polarity that rail 1 will be energized positively and rail 2 energized negatively. It should be pointed out at this time that, when the train enters eastern passing siding E, signal 8S will indicate its stop or red aspect and relay 8GP will release. Therefore, the energizing circuit for relay 8DP will be open at two points. With the reverse code being transmitted to section 6-7T of the polarity described, relay 6HTR will commence operating and relay 6DTR will release. Therefore, relay 6DTP will release and relay 6HTFP will pick up and establish a second energizing circuit for relay 6HR, which has been previously described. Accordingly, signal 6S will display its yellow aspect due to energization of its yellow lamp Y by a circuit which may be traced from positive terminal B of battery LB, over front contact b of relay 6HR, back contact b of relay 6DTP, and yellow lamp Y of signal 6S to negative terminal N of battery LB. Furthermore, with relay 6HR now picked up, relay 5ACR and 5BCR will commence operating and thereby generate and transmit thirty-seven and one-half code to section 4-5T. Accordingly, at signal location A, relay 4TR will commence operating at a thirty-seven and one-half code rate and relays 4TFP and 4HR will pick up. Therefore, relay 4ACR will commence operating as a reverse code transmitting relay, being energized at a thirty-seven and one-half code rate by capacitor Q over previously traced circuits. Furthermore, with relay 4HR picked up, signal 4S will now display its green aspect.

With relay 4HR now picked up, energy will be supplied to relay 3CTP at a 180 code rate by a previously traced circuit. Therefore, relay 3CTP will transmit normal 180 code to section 2-3T and, accordingly, relays 2TR and 2RCR will commence operating at a 180 code rate. With relay 2TR operating at a 180 code rate, relay 2DR will pick up, thereby opening the energizing circuit for relay 1DP at back contact b of relay 2DR. Therefore, the reverse code being transmitted by relay 2RCR will be of such polarity that rail 1 will be energized positively and rail 2 negatively. Furthermore, with relay 2DR picked up, signal 2S will now display its green aspect.

With the reverse code being transmitted to section 2-3T of the described polarity, relay 3HTR will commence operating and relay 3DTR

will release. Therefore, relay 3DTP will release and relay 3HTFP will pick up and thereby establish another energizing circuit for relay 3HR which has already been traced. Therefore, signal 3S will now display its yellow aspect due to the energization of the yellow lamp Y by a circuit including front contact b of relay 3HR and back contact b of relay 3DTP.

From the above description, it should be clear that when an eastbound train occupies the eastern passing siding E, the system will be restored to its normal condition with the exception of signal 8S which will be displaying its red aspect as shown in Fig. 2f. When the train vacates the eastern passing siding, signal 8S will clear up and the system will be restored to its normal condition.

Having described an eastbound train movement, let it now be assumed that a train enters the stretch of track from the east and moves in a westbound direction. When the train is in the eastern passing siding and approaching the stretch of single track, signal 8S will display a stop aspect and relay 8GP will release. However, since relay 7DR is picked up, there will be no effect upon the system and the system will continue to operate as it does in its normal unoccupied position, as shown in Fig. 3b.

When the westbound train occupies section 6-7T, any energy being supplied to that track section will be shunted by the wheels and axles of the train and, accordingly, the relays 7TR, 6DTR and 6HTR will all be released. With relay 7TR released, relay 7RCR will release as no energy will be supplied to it over its previously traced energizing circuit, and relay 7DR will be released due to the fact that insufficient energy is being supplied to it through the decoding unit 180DU. Accordingly, the previously traced circuit for energizing the green lamp G of signal 7S will become open and the circuit for energizing the red lamp R of signal 7S, which includes back contact a of relay 7DR, will be closed. At signal location C, with relays 6DTR and 6HTR released, relays 6DTP, 6HTFP and 6HR will all be released. Accordingly, the circuit for energizing the red lamp R of signal 6S, which includes back contact b of relay 6HR, will become established. Furthermore, with relay 6HR released, no energy will be supplied to relay 5ACR. Therefore, no energy will be supplied from track battery 5TB to track relay 4TR over the rails of section 4-5T. Accordingly, relay 4TR will release.

With relay 4TR released, relays 4TFP and 4HR will also release. It will be seen that with relay 4HR released and the remainder of the circuit arrangement at location A in the condition shown in Fig. 1a, relay 4ACR will commence operating at a 90 code rate in a manner substantially identical to that already described. Accordingly, at signal location C, track relay 5TR will commence operating at a 90 code rate and relay 5TFP will remain picked up and continue to energize relay 5HR. Accordingly, a circuit including front contact b of relay 5HR will remain established for energizing the green lamp G of signal 5S. With relay 4HR released, a circuit including back contact c of relay 4HR will be established for energizing the red lamp R of signal 4S. Furthermore, with relay 5HR picked up, relay 6CTP will be energized at a 180 code rate by a circuit which has already been traced. Therefore, relay 6CTP will continue to transmit 180 code to section 6-7T. However, with a train occupying the section, this

energy will be shunted by the wheels and axles of the train.

Upon the release of relay 4HR, a circuit for energizing relay 3CTP at a 75 code rate which circuit has already been traced from positive terminal B of battery LB, over front contact *a* of coder 75CT, back contact *b* of relay 4HR, and the winding or relay 3CTP to negative terminal N of battery LB will become established. Accordingly, relay 3CTP will commence operating at a 75 code rate and thereby transmit energy from battery 3TB to track relay 2TR over the rails of section 2-3T. With relay 2TR being energized at a 75 code rate, it will operate its contacts at a 75 code rate and accordingly supply energy to decoding unit 180DU at a 75 code rate. Decoding unit 180DU will supply insufficient energy to the relay 2DR, at a 75 code rate, to keep relay 2DR picked up and, accordingly, relay 2DR will release. Therefore the circuit for energizing the red lamp R at signal 2S will be established which circuit includes back contact *a* of relay 2DR. Upon the release of relay 2DR the circuit for energizing relay 1DP will become established and thereby cause relay 1DP to pick up and cause the reverse code being transmitted by relay 2RCR to now be of such polarity that rail 2 will be energized with energy of positive polarity and rail 1 will be energized negatively. Accordingly, relay 3DTR will commence operating and relay 3HTR will release. With relay 3DTR operating at a 75 code rate, relay 3DTFP will pick up. With relay 3DTFP picked up, relay 3HR will remain picked up as was previously described. Accordingly, a circuit will be established for energizing the green lamp G of signal 3S, which circuit has already been traced and which includes front contact *b* of relay 3HR and front contact *b* of relay 3DTFP. Fig. 3c shows the code assignments and signal aspects when a westbound train occupies section 6-7T.

When the westbound train vacates section 6-7T and occupies track section 4-5T, any energy supplied to section 4-5T will be shunted by the wheels and axles of the train and, accordingly, relay 4TR will remain released and relay 5TR will release. With relay 5TR released, relays 5TFP and 5HR will release and signal 5S will display its red aspect. Furthermore, with relay 5HR released, the circuit for supplying energy at a 75 code rate to the winding of the relay 6CTP will become established and relay 6CTP will commence supplying 75 code energy to section 6-7T. Accordingly, relay 7TR will commence operating at a 75 code rate. As has already been explained, with relay 7TR operating at a 75 code rate, relay 7DR will remain released and thereby continue to energize the red lamp R at signal 7S. At this time signal 8S will be displaying a clear aspect and, accordingly, relay 8GP will remain picked up. Therefore, the circuit for supplying energy to relay 8DP will remain established and it will remain picked up. As was explained earlier, with relay 7TR operating, relay 7RCR will operate and the two together will control the supply of energy from battery 7TB to the rails 1 and 2 of section 6-7T. With relay 8DP picked up the energy being supplied to section 6-7T will be of such polarity that rail 2 will be of positive polarity and the rail 1 of negative polarity and, of course, the energy will be coded at a 75 code rate. Therefore, at location C, relay 6DTR will commence operating at a 75 code rate and relay 6HTR will remain released. Accordingly, relays 6DTFP and 6HR will pick up. With re-

lays 6HR and 6DTFP picked up, signal 6S will display a green aspect due to the energization of its green lamp G over a circuit including front contact *b* of relay 6HR and front contact *b* of relay 6DTFP.

With relay 6HR picked up, relays 5ACR and 5BCR will commence operating so as to generate and transmit thirty-seven and one-half code to section 4-5T. However, with a train in the section, this energy will be shunted by the wheels and axles of the train. Therefore, as was previously stated, relay 4TR will remain released and relays 4TFP and 4HR will also remain released. With relay 4HR released, signal 4S will continue displaying its red aspect.

Furthermore, with relay 4HR remaining released, relay 3CTP will continue to be energized at a 75 code rate and transmit 75 code to relay 2TR. Accordingly, relays 2TR and 2RCR will operate at a 75 code rate, relay 2DR will remain released and relay 1DP energized. Therefore, signal 2S will continue to display a red aspect and 2RCR will continue to transmit a reverse 75 code of such polarity that rail 2 is energized positively and rail 1 negatively.

Therefore, at location A, relay 3DTR will continue to operate at a 75 code rate and relay 3HTR will remain released. Accordingly, relays 3DTFP and 3HR will remain picked up and relay 3HTFP will remain deenergized. Therefore, signal 3S will continue displaying its green aspect.

With relay 3HR picked up, relay 4ACR will continue transmitting 90 code to section 4-5T. Of course, with the train now occupying that section, its wheels and axles will shunt the 90 code energy. However, as explained with relation to an eastbound train movement, when the train vacates section 4-5T, the thirty-seven and one-half and 90 codes will scramble therefore assuring the system will reset for proper operation in a relatively short time.

The code assignments in the various sections and the aspects which the several signals will display with a westbound train in section 4-5T is shown in Fig. 3d.

When the westbound train vacates section 4-5T and occupies section 2-3T, any energy supplied to section 2-3T will be shunted by the wheels and axles of the train and accordingly relays 2TR, 3DTR and 3HTR will all be released. With relay 2TR now released, relay 2RCR will also release and relay 2DR will remain released and, accordingly, signal 2S will continue to display a red aspect. With relay 2RCR released, no reverse code will be transmitted to section 2-3T. With relays 3DTR and 3HTR released, relays 3DTFP, and 3HR will release, relay 3HTFP will remain released, and signal 3S will display a red aspect. With relay 3HR released, no energy will be supplied to code transmitting relay 4ACR and accordingly it will be released. Therefore, no code will be transmitted to section 4-5T from track battery 4TB over front contact *a* of relay 4ACR. Therefore, relay 5TR will remain released.

With relay 5TR released, no energy will be supplied to relay 5TFP or relay 5HR and these two relays will also remain released. With the relays at location C in this condition, relays 5ACR and 5BCR will continue to generate thirty-seven and one-half code in a manner identical to that already described. Accordingly, at signal location A, relay 4TR will commence operating at a thirty-seven and one-half code rate, relay 4TFP

will pick up and relay 4HR will also pick up. Therefore, signal 4S will display its green aspect. With relay 5TR released, relays 5TFF and 5HR will also be released and signal 5S will display a red aspect. With relay 4HR now picked up, relay 3CTP will commence being energized at a 180 code rate by a previously traced circuit. Therefore, relay 3CTP will transmit 180 code to section 2-3T. However, with a train now occupying that section, the 180 coded energy will be shunted by the wheels and axles of the train.

Furthermore, with relay 5HR released, the circuit for supplying energy to the winding of relay 6CTP at a 75 code rate will remain established and, therefore, relay 6CTP will continue to code energy from track battery 6TB to track relay 7TR at a code rate of 75. In a manner similar to that already described, with relays 6CTP and 7TR so operating, relay 7DR will remain released and thereby continue to energize the red lamp of signal 7S. With relay 7DR released the circuit for energizing relay 8DP will remain established. With relay 8DP picked up and relay 7TR operating at a 75 code rate, a reverse code at a 75 code rate of polarity such that rail 2 will be energized positively and rail 1 energized negatively will continue to be transmitted by relay 7RCR from the eastern headblock E to signal location C where this energy will cause relay 6DTR to continue operating and relay 6HTR to remain released. Accordingly, relays 6DTFP and 6HR will remain picked up, and thereby maintain the energizing circuit for the green lamp G of signal 6S. The code assignments for the various sections and the aspects which the several signals will display when a westbound train occupies section 2-3T are shown in Fig. 3e.

When the westbound train moves into the western passing siding W, the 180 code which was being transmitted by relay 3CTP will now be received by relay 2TR which will commence operating its contacts at a 180 code rate. Accordingly, relay 2DR will pick up and energize the green lamp G of signal 2S. Furthermore, relay 2RCR will commence operating at a 180 code rate. With relay 2DR picked up, relay 1DP will release and the reverse 180 code now being transmitted by relay 2RCR to signal location A will be of such polarity that relay 3HTR will commence operating and relays 3DTR and 3DTFP will release. Accordingly, relays 3HTFP and 3HR will pick up and energize the yellow lamp Y of signal 3S in a manner already described. Furthermore, with relay 3HR picked up, the previously traced circuit for connecting capacitor Q across the winding of relay 4ACR will be reestablished and relay 4ACR will commence transmitting a reverse thirty-seven and one-half code to location C where a thirty-seven and one-half code is being generated in the manner already described. Accordingly, relay 5TR will pick up and energize relays 5TFF and 5HR. Therefore, signal 5S will display its green aspect. Furthermore, with relay 5HR picked up, a previously traced circuit for energizing relay 6CTP 180 times per minute will be reestablished and relay 6CTP will transmit a 180 code to relay 7TR which will commence operating its contacts 180 times per minute. With relay 7TR so operating, relay 7DR will pick up and signal 7S will display its clear aspect. With relay 7DR picked up, relay 8DP will release. Furthermore, with relay 7TR operating its contacts 180 times per minute, relay

7RCR will commence operating its contact 180 times per minute and with relay 8DP released, will transmit a 180 reverse code of such polarity that relay 6HTR will commence operating at a 180 code rate and relay 6HR will remain picked up. Accordingly, as already described, relay 5ACR will continue transmitting thirty-seven and one-half code to relay 4TR. As can be seen from the description, when the westbound train moves into the western passing siding W, the system is restored to its normal condition except that signal 1S will display its stop aspect. The code assignments and signal aspects of the system when a westbound train occupies the western passing siding is shown in Fig. 3f. When the westbound train moves out of the western passing siding, signal 1S will clear up and the system will be restored to normal.

It will be clear that the additional conventional circuits, coded energy for the control of cab signal equipment could be included in my novel system. Furthermore, by the addition of conventional circuits at the headblock locations, provision can be made for following moves in my novel system:

It will also be clear that by polarizing the code being transmitted in section 4-5T, a third indication can be provided for signals 4S and 5S.

Although I have herein shown and described only one form of apparatus embodying my invention, it is to be understood that various changes and modifications may be made therein within the scope of the appended claims without departing from the spirit and scope of my invention.

Having thus described my invention, what I claim is:

1. In combination with a stretch of single track railway extending between two points, the rails of said track being divided by insulated joints into a first end section, an intermediate section and a second end section, a first coder for generating code of one code rate at the end of said intermediate section adjacent said first end section, a second coder for generating code of another code rate at the end of said intermediate section adjacent said second end section, a code halving means associated with each coder, means for generating reverse code at the first end of said intermediate section, code transmitting means at each end of said intermediate section, means for connecting said second coder and its associated code halving means to their associated code transmitting means except when said second end section is occupied, means for connecting said reverse code generating means to its associated code transmitting means when said stretch is vacant, means for connecting said first coder and its associated code halving means to their associated code transmitting means when said intermediate section or said second end section is occupied, code following track relay means at each end of said intermediate section operated by the energy supplied over the rails from the opposite end of said intermediate section, and a signal at each end of said intermediate section controlled by its associated track relay means.

2. In combination, a stretch of single track railway extending between a first and a second location, the rails of said stretch being divided by insulated joints into a first end section adjacent said first location, a second end section adjacent said second location and an intermediate section between said first and second end sections, track relay means associated with said first

and second end sections at the ends adjacent said first and second locations, respectively, reverse code generating means associated with said first and second end sections at the ends adjacent said first and second locations, respectively, means for reversing the relative polarity of the reverse code generated at the end of said end sections adjacent said first and second locations, respectively, when said stretch is vacant, track relay means selectively responsive to energy of opposite polarity at the end of said first and second end sections remote from said first and second locations, respectively, a first and a second coder for generating codes at different code rates located at the junction of said first end section and said intermediate section, a third and a fourth coder for generating codes at different code rates located at the junction of said intermediate section and said second end section, means for generating reverse code at the end of said intermediate section adjacent said first end section, a code halving means associated with said second coder, a code halving means associated with said third coder, code transmitting means located at each end of each section, means for connecting said second and fourth coders to their associated code transmitting means at the end of said first and second end sections remote from said first and second locations when said stretch is vacant or their associated section is occupied, means for connecting said first and third coders to their associated code transmitting means at the end of said first and second end sections remote from said first and second locations when either of the non-associated sections is occupied, said reverse code generating means at the end of said first and second sections adjacent said first and second locations, respectively, being continuously connected to its associated reverse code transmitting means, means for connecting said third coder and its associated code halving means to their associated code transmitting means except when said second end section is occupied, means for connecting said reverse code generating means at the first end of said intermediate section when said stretch is vacant, means for connecting said second coder and its code halving means to their associated code transmitting means when said second end section or said intermediate section is occupied, and a signal at each end of each section controlled by its associated track relay means.

3. In combination, a stretch of single track railway extending between a first and a second location, the rails of said stretch being divided by insulated joints into a first end section adjacent said first location, a second end section adjacent said second location and an intermediate section between said first and second end sections, track relay means associated with said

first and second end sections at the ends adjacent said first and second locations, respectively, reverse code generating means associated with said first and second end sections at the ends adjacent said first and second locations, respectively, means for reversing the relative polarity of the reverse code generated at the end of said end section adjacent said first and second locations when said stretch is vacant, track relay means selectively responsive to energy of opposite polarity at the end of said first and second end sections remote from said first and second locations, respectively, a first and a second coder for generating codes at a first and a second code rate, respectively, located at the junction of said first end section and said intermediate section, a third and a fourth coder for generating codes at said first and said second code rate, respectively, located at the junction of said intermediate section for generating reverse code at the end of said intermediate section adjacent said first end section, a code halving means associated with said second coder, a code halving means associated with said third coder, code transmitting means located at each end of each section, means for connecting said second and fourth coders to their associated code transmitting means at the end of said first and second end sections remote from said first and second locations when said stretch is vacant or their associated section is occupied, means for connecting said first and third coders to their associated code transmitting means at the end of said first and second end sections remote from said first and second locations when the non-associated sections are occupied, said reverse code generating means at the end of said first and second end sections adjacent said first and second locations, respectively, being continuously connected to its associated code transmitting means, means for connecting said third coder and its associated code halving means to their associated code transmitting means except when said second end section is occupied, means for connecting said reverse code generating means at the first end of said intermediate section when said stretch is vacant, means for connecting said second coder and its code halving means to their associated code transmitting means when said second end section or said intermediate section is occupied, and a signal at each end of each section controlled by its associated track relay means.
